UNITED STATES PATENT OFFICE.

WILLIAM O. DURBIN, OF KENMORE, NEW YORK, ASSIGNOR TO NATIONAL ANILINE & CHEMICAL CO., INC., OF NEW YORK, N. Y., A CORPORATION OF NEW YORK.

HIGH-PRESSURE HEATING.

Application filed December 5, 1925. Serial No. 73,451.

This invention relates to a method and a system of high temperature heating by the use of steam under high pressures and particularly to the control of the high pressures in such a system of steam heating.

In chemical plant operations, where heat is commonly applied by means of steam, high pressure steam is utilized for the high temperatures that are required. But, when the pressure in the plant steam mains is not sufficient, a separate source of high pressure steam must be provided.

It is an object of this invention to make use of low pressure steam in high pressure heating. A further object is a control of the steam pressure to effect a uniform temperature condition regardless of variations in the low pressure supply. Another object is the return of the excess high pressure steam to the low pressure source for recirculation or other uses. These and other objects will appear from the following description.

In brief, the invention comprises increasing the pressure of steam taken from a low pressure source by means of passing the low pressure steam through a steam compressor or other means thereby increasing its temperature and pressure the desired amount; utilizing the increased pressure steam for high temperature heating; and exhausting the steam through a balanced relief valve that maintains uniform pressure conditions in the high pressure system with variable back pressures from the low pressure source.

In the drawing accompanying this specification as an illustration of the invention.

Fig. 1 is a diagrammatic illustration of the heating system; and

Fig. 2 is a sectional view of a balanced relief valve used in the system.

The system comprises a low pressure steam supply main or source 1 from which a branch line 2 leads to a compressor or other means 3 for increasing the pressure to the desired high pressure. From the compressor the high pressure steam is led through a line 4 to the vessel 5 or other heat absorbing means. The vessel 5 is equipped with a condensate trap 5* which returns the condensate to the condensate return mains. Another line 6 conducts the steam to a relief valve 7 and the relief valve is connected by a return 8 to the low pressure supply main.

Uniform pressure and consequently the temperature at which condensation is effected in the heating of the vessel 5 is secured by a relief valve 7. It consists of a T-shaped casing 9 into one end of which is fitted a valve seat 10, having internal threads 11 for coupling to the high-pressure pipe line 6, and at the opposite end is a cylinder 12, in which a piston 13 reciprocates. The piston is provided with a plurality of packing grooves 14 to prevent leakage, and integral with one end of the piston is a valve stem 15 carrying the valve 16. A guiding stem 17 projects from the opposite end of the piston and contacts a lever 18. The lever is fulcrumed between a pair of projecting bosses 19, and is further restrained from side movement by prongs 20. The bosses 19 and prongs 20 are mounted on a removable cap 21, a passage 22 being provided, through which the stem 17 projects. The lever 18 is of sufficient length so that a weight W, movable on the lever, will maintain the desired pressure on the valve. The third opening 23 in the T is connected to the low pressure return 8. In place of the lever and the weight, a spring or other pressure applying means can be used.

The piston and the valve constitute a control member having opposing surfaces 24 and 25 exposed to the pressure of the low pressure line. Their effective areas are made equal and accordingly any pressure in one axial direction from the low pressure steam on the piston is counterbalanced by an equal pressure in the opposite axial direction on the valve. Consequently, as the valve movement is only effected by forces acting in the axial direction, the valve is not responsive to pressures in the low pressure line. The surface 26 of the valve is subjected to axial pressure from the high pressure line, while the surface 27 of the piston is open to the atmospheric pressures.

The effective opposing forces on the valve accordingly are the high steam pressure in one axial direction and the atmospheric pressure and the effective force of the weight W in the opposite direction. Consequently, when the high steam exceeds the opposing forces, the valve responds regardless of any variation in the low pressure line.

I claim:

1. A method of high pressure heating with variable low pressure steam which com-

- prises increasing pressure in the steam, utilizing increased pressure steam for high temperature heating, and returning the excess high pressure steam to the low pressure steam while maintaining uniform pressure in the high pressure steam.
2. A method of high pressure heating with variable low pressure steam which comprises increasing pressure in the steam, maintaining the increased pressure uniform irrespective of variations in the low pressure steam, and utilizing increased pressure steam for high temperature heating.
3. A system of high pressure steam heating which comprises a low pressure steam source, means connected to said source for increasing pressure in steam taken therefrom, heat absorbing means associated with said pressure increasing means, and means for maintaining a uniform increased pressure in said heat absorbing means.
4. A system of high pressure steam heating which comprises a low pressure steam source, means connected to said source for increasing pressure in steam taken therefrom, heat absorbing means associated with said pressure increasing means, means for maintaining a uniform increased pressure in said heat absorbing means, and means for

exhausting excess high pressure steam into 30 said low pressure steam source.

5. A system of high pressure steam heating which comprises a low pressure steam source, means connected to said source for increasing pressure in steam taken therefrom, heat absorbing means associated with said pressure increasing means, and means of exhausting excess high pressure steam into 35 said low pressure steam source, said means comprising a control member having opposed surfaces of equal area subject to low pressure and a second pair of opposed surfaces in which one surface is subject to the high pressure and the other surface to atmospheric pressure.

6. A system of high pressure steam heating which comprises a low pressure steam source, means connected to said source for increasing pressure in steam taken therefrom, heat absorbing means associated with 40 said pressure increasing means, and means of maintaining a uniform pressure in said heat absorbing means by a control member responsive to changes in the high pressure line but not responsive to changes of pressure in the 45 low pressure line.

In testimony whereof I affix my signature.
WILLIAM O. DURBIN.
